Primary Examiner—Bruce W. Dunkins**Assistant Examiner—Martha Thompson****Attorney, Agent, or Firm—Townsend & Townsend****[57]****CLAIM**

The ornamental design for a combined writing instrument set and container therefor, as shown and described.

DESCRIPTION

FIG. 1 is a left front perspective view of a combined writing instrument set and container therefor showing my new design;

FIG. 2 is a top plan view drawn to an enlarged scale;

FIG. 3 is a front elevational view of FIG. 2;

FIG. 4 is a right side elevational view of FIG. 2, the left side being a mirror image thereof;

FIG. 5 is a rear elevational view of FIG. 2;

FIG. 6 is a bottom plan view of FIG. 2;

FIG. 7 is a top plan view, drawn to the scale of FIG. 2, with the writing instrument set removed for convenience of illustration; and,

FIG. 8 is a front elevational view of FIG. 7.

FIG. 1.

FIG. 2.

FIG. 3.

FIG. 6.

FIG. 4.

FIG. 5.

FIG. 7.

FIG. 8.
